UNITED STATES PATENT OFFICE.

JOSEPH E. KIRKHAM, OF TOPEKA, KANSAS, ASSIGNOR TO KOEHRING COMPANY, OF MILWAUKEE, WISCONSIN, A CORPORATION.

SKIMMER-SCOOP CRANE.

Application filed October 3, 1924, Serial No. 741,345, and in Canada June 9, 1925.

A common type of machine used in excavating operations at the present time is known as a skimmer excavator. This machine, generally speaking, embodies a vehicular or traction support equipped with a substantially horizontal boom along which operates what is known as a skimmer scoop. The use to which this machine is put need not be recited because it is well known to those versed in the excavating machine art. It is notable, however, that in the operation of the skimmer scoop, generally speaking, the scoop is pulled outwardly from the point adjacent to the base of the machine, operating along the boom by which it is carried, and digging into the earth to scoop up the latter preparatory to raising the boom to elevate the load in the scoop and to dump the same. The movement of the scoop in the manner referred to creates a back-thrust length-wise of the boom and toward the base or traction support of the machine. A common type of traction support of skimmer scoop machine is a traction engine which by reason of its weight is able to withstand the back-thrust of the scoop in its operation, and above referred to, without even the immobilizing of the machine as regards the traction base or support feature. In said common type of skimmer scoop machines the scoop is susceptible of partial turning about a vertical axis provided for the supporting boom.

There are a number of advantages for the use of a skimmer scoop in conjunction with what may be generally characterized in the excavating art as rotary cranes, that is, a crane of the type comprising a car carried by a turn-table on a traction base, the car adapted to rotate a full revolution. A number of attempts have been made to adapt the skimmer scoop construction of excavator to a mounting thereof upon cranes of the rotary type, but considerable difficulty has been experienced in obtaining a practical construction of the above class of machine. One of the primary difficulties met with heretofore is involved in the fact that the rotary crane car or body which is adapted for ordinary crane uses with clam-shell, drag-line and shovel buckets, is a counter-balanced structure; that is to say the crane body or car is designed to receive a supporting boom at one end and weight means as well as a special distribution of the machinery of the car body are features employed to counter-balance the boom and

the loads which are handled by the particular kind of bucket associated with the boom. On account of the counter-balanced car or body construction of the ordinary rotary crane, when the skimmer scoop type of excavator has been mounted thereon heretofore, the back-thrust on the scoop supporting boom has been such as to tend to raise the front end of the machine and tilt the same over. In other words, the said back-thrust assists the counter-balancing parts of the machine to tip the latter. This disadvantage in the adaptation of a skimmer scoop construction of excavator to a rotary crane is well known today and the tipping over action is called "jack-knifing" of the crane, an operation characterizing the tendency of the scoop supporting boom and the car body of the crane to fold together, so to speak.

With the foregoing in mind, the primary object of the present invention has been to produce a construction in the way of a mounting with which a rotating crane may be equipped, said mounting being adapted to support a skimmer scoop boom in such a manner that the back-thrust produced on the boom in the dragging action of the skimmer scoop as it is pulled out will tend to bear down on the front end of the machine to oppose the forces of the counter-balancing features of the car body, to prevent tipping over of the machine as hereinbefore described. Essentially speaking, the mounting which I have designed involves the use of an auxiliary boom unit mounted on the end of the crane car or body, opposite its counter-balancing end and provided with a supporting arm with which the main skimmer scoop boom is connected, the said arm being deflected below the plane of the base of the car or crane body, whereby the back-thrust forces are directed downwards with tendencies to equalize with the counter-balancing means, the two, of course, being at opposite sides of the center pin of the crane turn-table.

The present invention resides in the special main boom mounting construction above referred to.

An additional important feature of the present invention is involved in one adaptation thereof where the main boom mounting is so designed that the auxiliary boom unit includes a boom that is adapted to form the boom of a power shovel and is, therefore, susceptible of interchangeable use for either the

purpose of a skimmer scoop supporting means or the purpose of a power shovel into which the crane may be converted when the skimmer scoop features are removed.

5 Another object of the invention has been to provide a skimmer scoop main boom mounting construction utilizing an auxiliary boom and arrangement of hoisting contrivance connected therefrom to the main boom whereby a more direct lift on the main boom may be obtained for the purpose of handling this boom as when elevating it to hoist the skimmer bucket for dumping.

10 Still another feature of design of the present invention involves the advantage of the main boom mounting construction by which the pivot or hinge point of the skimmer boom proper may be raised or lowered. The raising of the hinge point enabling the machine 15 to be employed with the skimmer scoop as an excavating means to trim up the shoulders of a road, notwithstanding that the machine itself rests on the subgrade of the road. This 20 feature of construction and advantage of the present design is not possible of attainment 25 with those machines that are at present commonly used for skimmer scoop work in this art.

30 In the accompanying drawings, Figure 1 is a side elevation of a skimmer scoop crane, embodying the essential features of the invention, in one adaptation, and susceptible of being converted into a power shovel.

35 Figure 2 is a fragmentary plan view, partly in section, showing more particularly the base member of the auxiliary boom mounting or structure.

40 Figure 3 is a sectional view of the parts shown in Figure 2.

45 Figure 4 is a side view like Figure 1, showing still another adaptation of the invention.

50 Figure 5 is a fragmentary view in front elevation showing more particularly the auxiliary boom supporting unit or structure.

55 Figure 6 is a view showing in full and dotted lines a certain amount of the range of adjustment of the auxiliary boom unit which adjustment may be employed for the stated purpose of trimming the shoulders of roads or the like.

60 Reference is made to the drawings as to Figures 1, 2 and 3, in which A designates the crane car or body, B, its traction support and C the skimmer boom. On the boom C is adapted to travel the usual skimmer scoop 1, pulled outwards longitudinally of the boom in the skimmer work by means of a drag cable 2, and adapted to be raised for its dumping action by means of a hoisting cable 3 that connects with the sheave 4 mounted on a vertical bracket 5 near the outer or free end of the boom C. The cable 2 winds about a drag drum 6 and the cable 3 about a hoisting drum 7.

65 The crane body or car A is supported on a

turn-table as usual, and is susceptible of full revolution movement upon the traction base B. So far as the construction of the scoop 1, its boom C and the operating features of the scoop are concerned, my excavator is substantially the same as common skimmer scoop excavators in commercial use today. The present invention lies primarily in the way I mount the parts 1 and C upon the crane body A.

70 For supporting the boom C to prevent the "jack-knifing" of the crane by the inward thrust of the boom C, I utilize the auxiliary boom supporting unit generally designated at D, and including the auxiliary boom 8, the off-standing supporting arm or base member 9, and the brace or truss rods 10. The parts 8, 9 and 10 virtually provide a triangular boom supporting unit. The base member 9 is preferably in the form of a casting itself in triangular form as seen in Figure 2, and is pivoted to the adjacent end of the crane body A by the pivots or journal pins 11. These same members 11 form the pivots to connect the legs 8^a of the foot of the boom 8 to the car or crane body A. In other words, the lower end of the boom 8 and the inner end of the base member 9 are coaxially mounted on the crane body A.

75 The skimmer boom C is pivotally connected by a journal member 12 with the outer or free end 9^a of the arm or base member 9 of the unit D.

80 Under normal conditions the member 9 inclines downwards so that the pivot 12 is in a plane below the base of the car or body A. Under these conditions it will be obvious that since the unit D is practically a rigid unit the forces generated by the back-thrust action of the scoop 1 on the boom C, when the scoop is 85 performing its work, tend to produce a downward thrust upon the adjacent end of the crane body A to which the unit D is pivoted. The down thrust transmitted to the end of the crane body A in the manner above stated by 90 the back-thrust of the boom C has the effect of counter-balancing the action of the weight means and machinery carried by the overhanging portion of the crane body or the end opposite that to which the unit D is pivoted. 95

100 Under these conditions there is no tendency on the part of the crane body and the boom C to "jack-knife" with the resultant disadvantages heretofore elucidated.

105 It is notable furthermore that the boom 8 is of a construction suitable for use as the ordinary dipper shovel supporting boom of a power shovel. On this account the unit D is of special advantage under practical conditions, because the skimmer scoop construction of crane utilizing it is susceptible of being quickly converted into a power shovel crane by merely removing the members 9 and 110 10 and taking off the skimmer scoop attachment. Thereafter the dipper stick and dipper 115

per features, with some specific parts that are always used to operate the same, may be applied to the boom 8 for the purpose of power shovel operation.

5 Figures 4 and 5 are referred to as showing a somewhat-modified construction of skimmer scoop crane, wherein the principles of structure are substantially the same as those hereinbefore presented respecting Figures 1 to 3 inclusive. In the modification of Figures 4 to 6, however, I employ an auxiliary boom supporting unit D' composed of a fabricated structure including spaced channels 8' converging toward their upper ends and connected by diagonal and other braces 8''. From the lower ends of the channels projects the arm or base member 9' which is composed of a couple spaced channels connected rigidly with the boom channels 8' by the plates 14. The arm or base member 9' has a central lug 15 which is pivotally connected at 12' with the skimmer boom C. Rigid brace straps 10' on this fabricated construction of unit D' perform the same functions practically as do the truss rods 10 in the first described adaptation of this invention.

The construction thus described has been found very efficient under practical conditions of service and has performed entirely without any jack-knifing results under working conditions.

It is notable in regard to both of the adaptations of the invention presented herein, that 35 the skimmer boom C is raised and lowered by the cable 3 which passes over a sheave or sheaves 16 at the peak of the boom member 8 or 8' as the case may be. Moreover, the mounting of the unit D or D', whichever 40 construction is used, is such that it projects a considerable distance laterally from the car body A and to a certain extent over the skimmer boom C. This is of considerable advantage in that by the arrangement described the hoisting cable means is enabled 45 to have a more direct lift on the boom, thus permitting it to be operated when being raised with greater ease than when the lifting forces are applied from a point lower 50 and in a vertical plane closer to the inner extremity of the skimmer boom.

By raising the base member 9 or 9' of the unit member D or the unit member D', respectively, the hinge point 12 or 12', respectively, 55 of the boom C may be correspondingly elevated whereby to adjust the boom C in a position elevated materially, somewhat after the manner shown in Figure 6. Under these conditions the shoulders at opposite sides of a road on the sub-grade of which the machine 60 may be working may be readily trimmed off. Lowering of the hinge point 12 or 12' as said shoulders are trimmed off will enable the boom C to be correspondingly lowered so as 65 to dig the shoulders down to the level of the

sub-grade on which the machine may be resting.

Having thus described my invention what I claim as new and desire to secure by Letters Patent is:

1. In a skimmer scoop crane, in combination, a traction support and a rotative car body thereon, a skimmer boom and skimmer bucket to operate on said boom, and means connecting the skimmer boom to the car body, including an auxiliary boom supporting unit pivoted to said body and having an off-standing arm, and means pivotally connecting the said arm at its outer end with the skimmer boom, the skimmer boom being free at all 75 times to swing on said pivotal connection toward and independently of the auxiliary supporting unit.

2. In a skimmer scoop crane, in combination, a traction support and a car body thereon, a skimmer boom and an out-digging skimmer bucket to operate on said boom, and means for connecting the skimmer boom to the car body including an auxiliary boom supporting unit pivoted to said body and comprising an off-standing arm inclined downwardly below the base of said car body, means connecting the said arm at its lower end with the skimmer boom, means for adjusting the auxiliary boom supporting unit to raise and lower the connecting means between the skimmer boom and the said arm, and means for preventing unintentional up-thrust of said connecting means.

3. In a skimmer scoop crane, in combination, a traction base, a car body mounted thereon and having counterbalancing means at one end, an auxiliary boom supporting unit mounted on said car body at its opposite end and including a member inclining downwards to a point below the plane of the base of said car body, an outdigging skimmer scoop attachment comprising a skimmer boom connected with the lower end of said member, and means movably connecting the auxiliary boom supporting unit to the car body operable to raise and lower said downwardly extending member, and to maintain it against unintentional movement in relation to the car body.

4. In a skimmer scoop crane, in combination, a traction base, a rotary car body mounted thereon and having counter-balancing means at one end, an auxiliary boom supporting unit of substantially triangular form connected by the one end of said car body, the base member of said unit inclining downwards to a point below the plane of the base of the car body, and a skimmer scoop attachment comprising a boom pivoted to the base 120 of said unit at substantially the lowest portion of the latter.

5. In a skimmer scoop crane, in combination, a traction base, a rotary car body mounted thereon and having counter-balancing

means at one end, an auxiliary boom supporting unit of substantially triangular form connected with the other end of said car body, the base member of said unit inclining downwards to a point below the base of the car body, a skimmer scoop attachment comprising a boom pivoted to the base of said unit at substantially the lowest portion of the latter, and means to rock the triangular supporting unit for elevating and lowering the point of connection of the skimmer boom with the base thereof.

6. In a skimmer scoop crane, in combination, a traction base, a rotary car body mounted thereon and having counter-balancing means at one end, an auxiliary boom supporting unit of substantially triangular rigid form connected to one end of said car body, the base member of said unit inclining downwards to a point below the plane of the base of the car body, a skimmer scoop attachment comprising a boom pivoted to the base of said unit at substantially the lowest portion of the latter, and hoisting means intermediate the upper end of said unit and the skimmer boom.

7. In a skimmer scoop crane, in combination, a traction base, a rotary crane body thereon counterbalanced at one end, a boom supporting unit mounted on the other end of said crane body and including a lateral base arm projecting below the plane of the base of the crane body, a skimmer boom connected with the lower portion of the said base arm, an outdigging skimmer bucket to travel on said boom, means to elevate the skimmer boom, and means for adjusting the said base of the boom supporting unit.

8. In a skimmer scoop crane, in combination, a traction base, a rotary type crane body thereon counterbalanced at one end, a boom supporting unit mounted on the other end of said crane body and including a boom inclining upwardly and a lateral base arm projecting below the plane of the base of the crane body and rigidly connected with the boom to transmit resistance forces received from a skimmer bucket downwards onto the crane body, a skimmer boom connected with the lower portion of the said base arm, a skimmer bucket to travel on said boom, means to elevate the skimmer boom, means for adjusting the said base of the boom supporting unit comprising a pivotal connection between the unit and the crane body.

9. In a skimmer scoop crane, in combination, a traction support and a car body thereon, a skimmer boom and skimmer bucket to operate on said boom, and means for connecting the skimmer boom to the car body including an auxiliary boom supporting unit pivoted to said body and comprising an off-standing arm extending outward from the base of said car body, means connecting the said arm at its outer end with the skimmer

boom, said boom supporting unit including a boom upon which the said arm is rigid but detachable and said last-named boom being of the type adapted to receive power shovel operating instrumentalities on removal of the skimmer scoop features and said arm.

10. A skimmer scoop crane comprising a traction base, a crane body adapted to revolve upon said base and having boom and load counter-balancing means at one end, a skimmer scoop attachment for said crane disposed at the other end of the crane body and comprising a skimmer scoop boom and a skimmer scoop adapted to operate thereon, and an adjustable mounting between said skimmer boom and the end of the crane body on which it is carried arranged to transmit the back-thrust of the boom incident to the movement of the scoop, to the crane body, to act upon the latter in a direction opposite to the normal action of the counter-balancing means, whereby "jack-knifing" of the skimmer boom and crane body are prevented, means for adjusting said mounting to raise the point of connection between the same and the skimmer boom or lower said point of connection, said point of connection being located beneath the plane of the bottom of the crane body, and hoisting means for the skimmer boom.

11. A skimmer scoop crane, comprising a traction support, a crane body adapted to revolve upon said support, a skimmer scoop boom mounted at an end of said crane body, a skimmer scoop operating on said boom, and connecting means between the crane body and the skimmer scoop boom located to deliver back-thrust from the boom to the crane body substantially in the planes of the base of the body, the skimmer scoop boom having its outer end free to move upward independently of its connection with the body.

12. A skimmer scoop crane, comprising a traction support, a crane body rotative thereon, a skimmer scoop boom extending from one end of the crane body, a skimmer scoop operating on said boom, means for raising and lowering the boom adapted to be operated from the crane body, and a supporting unit establishing a pivotal connection between the skimmer boom and the crane body and comprising an upwardly extending auxiliary boom pivoted to the crane body and having an outwardly extending base arm to which the skimmer boom is directly pivoted, and means connecting the said base arm with the said auxiliary boom so that endwise forces acting upon the skimmer boom in the direction of the crane body tend to pull downwards on the auxiliary boom and transmit a corresponding downward thrust upon the end portion of the crane body at which the skimmer boom is disposed, whereby to prevent the endwise forces acting on the skimmer boom from tilting the crane body over toward the end there-

of opposite that at which the skimmer boom is arranged.

13. A skimmer scoop crane substantially as claimed in claim 12 combined with means for changing the elevation of the said auxiliary boom and its base arm to correspondingly change the elevation of the pivotal connection between the skimmer boom and said base arm, whereby the path of movement of the skimmer scoop may be adjusted in a vertical direction.

14. In apparatus of the class described, the combination, with a pivotally mounted counter-balanced crane body, of a triangular auxiliary boom unit pivoted to the crane body in position for opposing the stress of the counter-balance thereof, the said pivot being located substantially at one angle of the auxiliary boom unit, a scoop boom pivoted to the auxiliary boom unit substantially at another angle thereof, and a flexible connection between the outstanding portion of the scoop boom and the third angle of the auxiliary boom.

15. In apparatus of the class described, the combination, with a pivotally mounted counter-balanced crane body, of a triangular, auxiliary boom unit describing substantially an isosceles triangle with the base line relatively short and lowermost, means pivotally connecting said auxiliary boom unit substantially at one end of said base line to the crane body at substantially the base thereof, and a scoop boom pivoted to and outstanding from said auxiliary boom unit at substantially the opposite end of said base line.

16. Apparatus substantially as claimed in claim 15 in which said base line is inclined downward from its engagement with the crane body.

17. Apparatus substantially as claimed in claim 15 combined with a flexible elevating connection between the free outer end portion of the scoop boom and the outstanding apex of the auxiliary boom unit.

18. In apparatus of the class described, the combination, with a pivotally mounted counter-balanced crane body, of a rigid triangular auxiliary boom unit describing substantially an isosceles triangle with the base line lowermost, means pivotally connecting said auxiliary boom unit to the crane body, and a scoop boom pivoted to said auxiliary boom unit and outstanding therefrom.

19. In apparatus of the class described, the combination, with a pivotally mounted counter-balanced crane body, of an auxiliary boom pivoted to said body at a point to oppose the stresses of the counter-balance and having a relatively rigid extension projecting below the plane of the pivot of the crane body, a scoop boom pivoted to said extension below said plane and outstanding from said extension, and a supporting and elevating cable for the outer portion of the scoop boom ex-

tending about and sustained by the upper extremity of the auxiliary boom, the said scoop boom being free to swing upon its pivot toward said auxiliary boom, whereby back thrust on the scoop boom may be delivered to the crane body only as stresses opposing the counter-balance stresses.

20. In apparatus of the class described, the combination, with a counter-balanced crane body, of a scoop boom outstanding therefrom, a scoop carried by said boom, means engaging the boom for actuating the scoop, and a plurality of articulated connections comprising a plurality of rigid members angularly related to each other between the boom and the crane body.

21. In apparatus of the class described, the combination, with a counter-balanced crane body, of a scoop boom outstanding therefrom, an auxiliary boom carried by said crane body, and a flexible supporting connection between the outer portion of the scoop boom and the auxiliary, the scoop boom being pivotally connected to the auxiliary boom as the means of its connection to the crane body.

22. In apparatus of the class described, the combination, with a counter-balanced crane body, of an auxiliary boom pivoted to the body in the plane of the lower portion thereof, a scoop boom pivoted to the auxiliary boom as a means of its connection to the crane body and outstanding from the crane body, and a flexible supporting connection between the outer portion of the scoop boom and the auxiliary boom.

23. In apparatus of the class described, the combination, with a counterbalanced crane body, of a boom outstanding substantially horizontal from the crane body, a plurality of pivotal connections between the crane body and boom spaced in the general direction of the length of the boom, a digging instrument reciprocally mounted on the boom, an actuating cable for the digging instrument laced past the outer end portion of the boom, and a guide for said cable substantially at the outer end portion of the boom whose axis of rotation is spaced above the longitudinal axis of the boom.

24. In apparatus of the class described, the combination, with a counterbalanced crane body, of a boom outstanding substantially horizontal from the crane body, a plurality of pivotal connections between the crane body and boom spaced in the general direction of the length of the boom, a digging instrument reciprocally mounted on the boom, an actuating cable for the digging instrument laced past the outer end portion of the boom, a guide for said cable substantially at the outer end portion of the boom spaced above the longitudinal axis of the boom, and means for preventing the outer pivotal connection of the boom from unintentional up-rust.

25. In combination, a crane body, a boom

outstanding and spaced therefrom, an excavating device cooperating with said boom, a supporting member between the body and boom and pivoted to the body and to the boom, and means for resisting thrusts in either direction tending to shift the location of the pivotal connection of the supporting member to the boom.

26. In combination, a crane body, a boom outstanding and spaced therefrom, an excavating device cooperating with said boom, a supporting member between the body and boom and pivoted to the body and to the boom, means for resisting thrusts in either direction tending to shift the location of the pivotal connection of the supporting member to the boom, and means for swinging the sup-

porting member on its pivotal connection to the crane body.

27. In combination, a crane body, a boom outstanding and spaced therefrom, an excavating device cooperating with said boom, a supporting member between the body and boom and pivoted to the body and to the boom, means for resisting thrusts in either direction tending to shift the location of the pivotal connection of the supporting member to the boom, means for swinging the supporting member on its pivotal connection to the crane body, and independent means for swinging the boom on its connection to the supporting member.

In testimony whereof I affix my signature.

JOSEPH E. KIRKHAM.
